(57) CLAIM

I claim the ornamental design for jeans, as shown and described.

DESCRIPTION

FIG. 1 is a front view of jeans showing my new design;

FIG. 2 is a back view thereof;

FIG. 3 is a right side view thereof; and,

FIG. 4 is a left side view thereof.

The top and bottom of the jeans are flat and unornamented.

The dashed lines shown on the jeans represent stitching.
